UNITED STATES PATENT OFFICE.

SIMON COOPER, OF BROOKLYN, NEW YORK, ASSIGNOR TO COOPER TEA PACKET CO., INC., OF BROOKLYN, NEW YORK, A CORPORATION OF NEW YORK.

METHOD OF PACKETING TEA OR THE LIKE.

Application filed November 1, 1921. Serial No. 512,161.

To all whom it may concern:

Be it known that I, SIMON COOPER, a citizen of the United States, residing at Brooklyn, in the county of Kings and State of New York, have invented certain new and useful Improvements in Methods of Packeting Tea or the like, of which the following is a specification.

This invention relates to the packeting 10 of materials, to a new and improved form of packet, and particularly to a method for facilitating and increasing the speed of production of packets of a general type such as is used in packeting tea in individual 15 containers.

In a companion application Serial No. 454,707 filed March 23, 1921, there is disclosed and claimed a packet for tea or other material formed of a blank folded on 20 itself and stitched along the meeting edges. The blanks for such packets are individually formed and individually operated on in the making of the packets. In the 25 present invention an elongated blank is used which is folded longitudinally on itself and, by a series of stitching and charging or 30 filling operations, a series or succession of filled packets is rapidly produced in the blank or strip of material, the individual packets being separated from each other only after they have been completely formed and filled as indicated.

By this method of producing the filled 35 packets the speed of production is greatly increased over the production of packets or containers of a similar general nature heretofore known in the art. In addition the packet forming operations are more easily and economically accomplished and a practical and inexpensive packet is obtained.

Other features of the invention will be hereinafter referred to.

In the drawings in which two preferred forms of the invention are illustrated.

Figure 1 is a view in plan of a suitable blank and showing the progress of a series of operations thereon to convert the blank into a plurality of packets for tea or other material.

Figure 2 is a view in side elevation of a completed filled packet.

Figure 3 is a view in cross-section taken on the line 3—3 of Figure 1 and showing the operation of filling or charging one of the 55 packet sections of the blank.

Figure 4 is a view in cross-section taken on the line 4—4 of Figure 1 and showing the operation of stitching or closing one side of the packet.

Figure 5 is a view in plan showing a blank 60 and a series of packets formed therein in which the shape or conformation of the packets is a modification from that shown in Figure 1.

Referring to the drawings for a more 65 particular description a blank or strip of material 5 is folded on its longitudinal median line 6 to bring the two plies of the strip thus formed into superposed relation with their free edges in or substantially in 70 alinement or engagement with each other as at 7 in the drawings. The longitudinally folded blank or strip thus provided is formed into a series or succession of packet 75 forming sections by the simple operation of running transverse lines of stitches across the folded strip of material between the lateral edges thereof as at 8 in Figure 1 of the drawing. The section of the strip which is thus formed has, as will be clear, 80 a closed edge formed by the fold in the folded strip and two closed sides formed by the two lines 8 of stitching as indicated. The fourth side of the packet is similarly 85 closed by a line of stitching such as is indicated at 9 in Figure 1 of the drawing. The stitching operation may be performed by first forming the two transverse lines 8 of stitching when the tea or other material 90 is charged or filled into the packet through the remaining open edge formed by the free edges of the plies of the strip. The filling operation having been performed, the open side of the packet may be closed by then 95 running the third line of stitching 9 along the edge and along the two transverse lines of stitching 8.

A preferred way, however, of performing the operation of forming the packets is indicated in Figure 1 of the drawing. In this 100 method of operation the operation of stitching is begun at an upper right-hand corner of a packet section as at 10 in Figure 1 of the drawing and proceeded with to form the first transverse lines of stitching 8. The line 8 having been completed, the stitched line 9 is then produced, the line being extended to a point beyond the mass of tea or other material 11 which has been 105 charged or filled into place previous to the 110

beginning of the stitching operation. Having finished the line of stitching 9 the line of stitching is then diverted at right angles to produce the second transverse line 8, which as will be seen, accomplishes the completion of the packet and wholly encloses the mass of tea on all sides.

The operation just described is repeated again and again to enclose each individual 10 mass of tea 11 in the series of charges that are fed into position between the plies of the blank at the proper intervals through the operation of a suitable filling machine whose discharge spout is indicated at 12 15 in the drawing. It will be seen that the adjacent lines of stitching 8 between adjacent packets are spaced from each other a sufficient distance to provide for a subsequent separating or severing operation 20 which may be accomplished by any suitable shearing, cutting or other device indicated at 13 in Figure 1 of the drawing.

In the form of the invention illustrated in Figure 1 the individual packets formed 25 are square or substantially square in conformation. It will be clear that the particular shape as well as the particular size of the packets can be varied between wide limits within the invention.

30 Another desirable form for packets suitable for holding tea is that shown in Figure 5 of the drawing in which it will be seen that the transverse lines of stitching 8 which are produced in the blank 5 have an inclined or 35 oblique position as contrasted with lines of stitching 8 in Figure 1 which are substantially perpendicular to the lateral edges of the blank.

In either one of the forms of the invention indicated I prefer to produce the 40 stitched lines from thread which has been attached by stitching or otherwise to a suitable identification tag 14, the tag being separated from the packet by a length of the 45 stitching thread or cord 15 which provides a suitable supporting member by means of which the packet may be handled.

It will be seen that the invention includes a method of preparing packets for tea or 50 other material in which a relatively high

speed of production can be accomplished, the formation of the completed packets in series or succession in an elongated strip of material greatly increasing the efficiency and economy of operation over heretofore known methods in which the blanks for the packets were individually formed.

What is claimed is:

1. That method of making tagged completely closed packets of tea or like material, which consists in folding longitudinally an elongated blank, depositing charges of the material in spaced apart relation between the plies of the blank, running a line of stitching through both plies from the folded edge of the blank at one side of the charge, around the charge, and back to the fold, extending the stitching thread at one side of the charge beyond the folded edge and free of the blank, and attaching to the extended thread a tag. 70

2. That method of making tagged and filled packets, which consists in folding longitudinally an elongated blank of textile material, in depositing spaced apart 75 charges of filling material between the plies of the blank at one section thereof and running a line of stitching from the folded edge of the blank around a charge of material and back to the folded edge. 80

3. That method of producing a filled packet which consists in preparing a folded blank of textile material with a charge of filling material contained between the plies of the fold, and running a line of stitching 85 from the folded edge of the blank around the charge of material and back to the folded edge. 90

4. That method of producing a filled tea packet which consists in preparing a folded rectangular blank of open-mesh fabric with a charge of tea contained between the plies of the fold, running a line of stitching from the folded edge of the blank around the charge of material and back to the folded edge, and then extending the stitching thread and attaching it to a tag element. 95

In testimony whereof I affix my signature.

SIMON COOPER.
